UNITED STATES PATENT OFFICE.

FREDERICK U. SEEGER, OF NEW YORK, N. Y., ASSIGNOR TO SAMUEL GABRIEL SONS & COMPANY, OF NEW YORK, N. Y., A CORPORATION OF NEW YORK.

TOY BLOCK.

1,314,541.

Specification of Letters Patent. Patented Sept. 2, 1919.

Application filed April 19, 1918. Serial No. 291,202.

To all whom it may concern:

Be it known that I, FREDERICK U. SEEGER, a citizen of the United States, and resident of the borough of Manhattan, city, county, 5 and State of New York, have invented certain new and useful Improvements in Toy Blocks, of which the following is a specification.

This invention relates to toy blocks, such 10 as alphabet or picture blocks, for the instruction and amusement of children.

It is the primary object of the present invention to provide a block of this character, constructed of cardboard or similar material, in a simple and inexpensive manner, 15 and which will be of great durability.

The invention more particularly comprehends a block constructed of three primary elements consisting of a strip of bendable 20 material to produce the four sides of the block and two end pieces insertible between the body walls having coöperating means to provide a very secure and rigid connection between the several parts.

It is a further general object of my invention to provide a non-collapsible block 25 which will be light in weight and will not be likely to injure one struck thereby, even though the block may be thrown with considerable force.

With the above and other objects in view, the invention consists in the improved construction, combination and relative arrangement of the several parts, as will be herein 30 after more fully described, subsequently claimed and illustrated in the accompanying drawing, in which similar reference characters designate corresponding parts throughout the several views, and wherein

Figure 1 is a plan view of the body blank 35 of my improved block;

Fig. 2 is a perspective view of the block with certain parts broken away and others omitted;

Fig. 3 is a detail perspective view of one 40 of the end walls;

Fig. 4 is a horizontal section through the block, one wall thereof being broken away, and

Fig. 5 is an enlarged fragmentary perspective view illustrating the manner of assembling and connecting the body and end walls.

Referring in detail to the drawing, 5 designates a strip of cardboard or other suitable

material having the necessary structural rigidity, but capable of being bent. This material upon one side is slightly creased at equidistantly spaced points as shown at 6', and the sections of the material are bent inwardly toward the creases to provide a substantially rectangular body structure having the walls designated 6. By slightly creasing the strip 5, instead of deeply scoring the same and bending the sections inwardly, the material at the outer side of the body and at 60 the juncture of the wall 6 is not broken, but presents a smooth continuous corner surface. Thus, I obtain a maximum of strength in the block structure, so that it is capable of 65 resisting severe strains.

Each of the body walls 6 at its opposite ends is centrally recessed or mortised, as indicated at 7, the depth of the mortises being equivalent to the thickness of the material. Preferably, a single mortise is formed in 70 each end edge centrally of the block wall.

The end walls 8 are each stamped or cut from a cardboard sheet, so as to fit tightly within the end of the block body, and with the marginal edges of said end wall frictionally contacting with the inner faces of the respective body walls. The end wall is provided upon each of its edges at the center thereof with a tongue or tenon 9 adapted to fit tightly within the mortises 7 in the body 75 walls of the block. These tenons are also of a depth equivalent to the thickness of the material. Thus, it will be apparent that the outer surfaces and edges of the end walls will be flush with the surfaces and edges of 80 the body walls. If desired, a suitable adhesive may be applied to the edges of the mortises 7 and the tenons 9, though this is not at all necessary, as the tight frictional engagement of the end walls and the tenons thereon with the body walls of the block will 85 securely retain the several walls in assembled relation.

After the parts of the box structure have been thus assembled, strips of paper, linen 100 or other suitable material 10 are pasted or adhesively secured along the corners of the block walls and upon the contiguous angular meeting faces of said walls. Finally, a lithographed paper sheet is adhesively secured upon the body walls of the block and 105 also upon the end walls thereof, said sheet having delineated thereon letters of the al-

phabet, animals, or other objects, which will be instructive and amusing to children. This lithographed sheet indicated in the drawing at 11 extends over and completely 5 covers all surfaces of the block wall and likewise the reinforcing corner strips 10.

From the foregoing description considered in connection with the accompanying drawing, the construction and manner of 10 assembling the several parts of my improved block will be clearly and fully understood. The block may, of course, be made in many different sizes, and while I have above referred to a simple rectangular 15 block structure, it is manifest that the several features of my invention can also be advantageously employed in the manufacture of toy blocks of various other forms. I have found, in practice, that a 20 block constructed as herein described is exceedingly durable and will withstand a great amount of rough handling. At the same time the block can be manufactured at nominal cost, and being very light in 25 weight will not damage or mar furniture or injure persons with whom it may come in contact, though thrown with considerable force.

I have herein illustrated and described a 30 preferred embodiment of the invention, but as the improved block may likewise be exemplified in many other analogous constructions, it is to be understood that I reserve the privilege of adopting all such legitimate changes in the form, construction 35 or arrangement of the various parts as may be fairly embodied within the spirit and scope of the invention as claimed.

I claim:

- 40 1. A non-collapsible block comprising a body strip of material adapted to be bent to form the side walls of the block structure, and end members of similar material adapted to be fitted between the body walls 45 at the opposite ends thereof, said end members and the body walls having co-operative means centrally formed on their proximate edges to rigidly retain the parts in assembled relation.
- 50 2. A non-collapsible block comprising a body consisting of a cardboard strip adapted to be bent at spaced points to form the side walls of the block, each of said walls having mortises centrally formed in its end edges, and end walls adapted to be fitted 55 between the ends of said side walls and each having tenons formed on its edges for engagement in the mortises in the respective side walls, the length of said tenons and

the depth of the mortises corresponding to 60 the thickness of the block walls.

3. A non-collapsible block comprising a body consisting of a cardboard strip creased at spaced points to provide portions bendable inwardly upon the creased side of the 65 strip toward each other to form the side walls of the block, each of said walls having mortises centrally formed in its end edges, and end walls adapted to be fitted between the ends of said side walls, and each having 70 a single tenon centrally formed on each of its edges for engagement in the mortises in the respective side walls, the length of said tenons and the depth of the mortises corresponding to the thickness of the block 75 walls.

4. A non-collapsible block comprising a body consisting of a cardboard strip creased at spaced points to provide portions bendable inwardly upon the creased side of the 80 strip toward each other to form the side walls of the block, each of said walls having mortises centrally formed in its end edges, end walls adapted to be fitted between the ends of said side walls, and each 85 having a single tenon centrally formed on each of its edges for engagement in the mortises in the respective side walls, the length of said tenons and the depth of the mortises corresponding to the thickness of the block 90 walls, and reinforcing strips adhesively secured over the meeting edges of the side walls and end walls and along the juncture of the side walls with each other.

5. A non-collapsible block comprising a 95 body consisting of a cardboard strip creased at spaced points to provide portions bendable inwardly upon the creased side of the strip toward each other to form the side walls of the block, each of said walls having mortises centrally formed in its end edges, end walls adapted to be fitted between the ends of said side walls, and each having a single tenon centrally formed on each of its edges for engagement in the mortises in the 100 respective side walls, the length of said tenons and the depth of the mortises corresponding to the thickness of the block walls, reinforcing strips adhesively secured over the meeting edges of the side walls and end 105 walls and along the juncture of the side walls with each other, and a lithographed paper sheet adhesively secured upon the block walls and over said reinforcing strips.

In testimony that I claim the foregoing as 115 my invention, I have signed my name thereto.

FREDERICK U. SEEGER.
